(57) **CLAIM**

The ornamental design for a display screen with animated graphical user interface, as shown and described.

DESCRIPTION

FIG. 1 is the first image in a sequence for a display screen with animated graphical user interface showing our new design;

FIG. 2 is the second image thereof;

FIG. 3 is the third image thereof;

FIG. 4 is the fourth image thereof;

FIG. 5 is the first image of an alternative embodiment of a sequence for a display screen with animated graphical user interface showing our new design;

FIG. 6 is the second image thereof;

FIG. 7 is the third image thereof;

FIG. 8 is the fourth image thereof;

FIG. 9 is the first image of an alternative embodiment of a sequence for a display screen with animated graphical user interface showing our new design;

FIG. 10 is the second image thereof;

FIG. 11 is the third image thereof;

FIG. 12 is the fourth image thereof;

FIG. 13 is the first image of an alternative embodiment of a sequence for a display screen with animated graphical user interface showing our new design;

FIG. 14 is the second image thereof;

FIG. 15 is the third image thereof;

FIG. 16 is the fourth image thereof;

FIGS. 17-19 are enlarged views of the solid line subject matter of FIGS. 2-4, shown separately for completeness of illustration;

FIGS. 20-22 are enlarged views of the solid line subject matter of FIGS. 6-8, shown separately for completeness of illustration;

FIGS. 23-25 are enlarged views of the solid line subject matter of FIGS. 10-12, shown separately for completeness of illustration; and,

FIGS. 26-28 are enlarged views of the solid line subject matter of FIGS. 14-16, shown separately for completeness of illustration.

The outermost broken line and the broken line showing of the circular feature illustrate an electronic device. The remaining broken lines illustrate portions of the animated graphical user interface and portions of the display screen. None of the broken lines form part of the claimed design.

1 Claim, 28 Drawing Sheets
